HYDRAULICALLY ACTUATED MEMBER AND
SPEED CONTROL THEREFORHarry F. Vickers, Detroit, Mich., assignor to
Vickers, Incorporated, Detroit, Mich., a cor-
poration of MichiganOriginal application June 12, 1931, Serial No.
543,908. Divided and this application March 8,
1939, Serial No. 260,526

9 Claims. (Cl. 60—52)

This invention relates to a hydraulically actuated member and speed control therefor, and has to do particularly with liquid actuated devices which are subject to a variable speed or a variable load.

This application is a division of my copending application Serial No. 543,908, filed June 12, 1931, since abandoned.

Heretofore, in the control of the speed of liquid actuated devices, such as machine tools and the like, it has been the practice to make use of systems embodying either a variable displacement pump or a constant displacement pump. In systems using variable pumps, it is the practice to set the pump corresponding to a certain load and predetermined speed. Theoretically, such variable pump should maintain a constant speed of the liquid actuated element regardless of a varying load, but practically, there is a change in slippage in such pumps which results in a slowing down when an increased load is met or an increase in speed equivalent to the amount of slippage when load is released. In practice, in systems using variable pumps, fairly good results are often obtained when the work is first set up, but when the oil warms up and thins, and as the tools become dull, there is a noticeable slowing up due to a change in the slippage in the variable pump.

In control systems utilizing constant displacement pumps, present practice is to control the speed of the actuated member by the use of throttle valves placed either in the intake or discharge sides of the actuating cylinder. In such systems, however, it has been impossible to maintain a constant speed of actuated member due to change in differential pressure across the throttle valve with the result that the speed varies with the change in load on actuated member.

It is the object of the present invention to provide means operating independently of the particular type of pump used and independently of the viscosity of the liquid used, to uniformly and positively control the speed of any liquid actuated member; this control of speed being either uniform regardless of the load, or variable relative to any change in load. More specifically, the present invention utilizes the principle that if a given pressure differential is maintained across a given size orifice the flow through said orifice will remain constant.

An important feature of the present invention resides in the fact that my speed control means is placed in the discharge side of the system in 55

order to prevent undesired movement in case of change in the load from positive to negative, although it will be understood that very efficient results may be obtained if the unit is placed ahead of the liquid actuated device in any other case.

My complete system, as contemplated in the present invention, embodies a liquid actuated member such as a machine tool element which is subjected to a variable load either positive or negative during its movement in any given direction, a source of fluid supply under pressure, an orifice regulable to control the flow of liquid therethrough, and hence the speed of the liquid actuated element, and means operating in combination with the other elements of the system to positively control the pressure differential across the orifice to maintain or control the predetermined speed. This means embodies a hydrostatic pressure regulating valve, preferably in combination as a single unit with a variable orifice, said hydrostatically operating valve being so arranged and proportioned that any change in pressure due to a change in load can be made to increase, decrease or maintain the pressure in a certain part of the valve and hence cause the differential pressure across the orifice to either increase, decrease, or maintain constant the speed of the liquid actuated element, as desired.

Other features, including the application of the balanced pressure regulating valve to and in combination with the general system and the structural details of the valve itself, will be more clearly brought out in the specification and 35 claims.

In the drawings:

Fig. 1 is a somewhat diagrammatic view of a complete liquid circulating system embodying the present invention, and showing particularly the 40 manner of connecting my speed control valve into the system whereby to control the speed of the liquid actuated element in one direction.

Fig. 2 is a sectional view of my hydrostatic or speed control valve as embodied in a single complete unit, the balanced valve being shown in raised seated position.

Fig. 3 is a front elevation of the complete unit and showing the adjustable indicating lever for regulating the size of the discharge orifice.

Fig. 4 is a fragmentary sectional view of the end of the balanced valve and showing a modified manner of varying the effective diameter of one end of the valve.

Fig. 5 is a somewhat diagrammatic assembly view of a circulating system embodying the pres-

ent invention and showing the manner of connecting my speed control valve into the discharge side of the system, and controlling the speed of the liquid actuated member in opposite directions of movement.

Fig. 6 is a view similar to Fig. 5, but illustrating the manner of connecting the speed control unit into the intake side of the system.

First taking up the description of the speed control or hydrostatic valve as an integral unit of manufacture, and as best shown in Figs. 2 and 3, it will be seen that said valve consists of a housing 2 which is provided with a chamber 3 in communication with the incoming liquid and a chamber 4 for connecting a balanced inlet valve 5 and a variable orifice outlet valve 6. This outlet valve 6 controls the volume of liquid passing into the outlet 7.

The balanced valve 5 is connected by means of a stem 8 to a piston 9, the diameter A^1 of the stem at the point 10 being predetermined relative to the effective diameter A^2 of the valve 5 at its valve seat. Under usual conditions, the diameter of the portion 10 of the valve stem will be equal to the effective diameter of the valve 5, but such respective diameters may be varied as will be later described. In Fig. 2, diameter A^2 is shown smaller than diameter A^1 . A coil spring 11 of predetermined pressure is so positioned as to normally tend to open the valve 5. The chamber 4 is in direct communication with a chamber 12 on one side of the piston 9 by means of a passageway 13 so that the strength of the spring 11 as balanced against the pressure upon the area of the piston 9 determines the opening of the valve 5.

The space 14 on the other side of the piston 9 is in communication, by means of the passageway 15, with the outlet passageway 7 to compensate for any back pressure under any operating conditions, as, for instance, when a long pipe connected to the outlet 7 would set up a material amount of resistance. The back pressure in the line 7 will vary and one of the variants will be the length of the pipe 7, but as the back pressure in the pipe 15 is effective against the top of piston 9 it will be seen that the combination of the spring 11, piston 9, conduit 13, valve 5, and orifice 6 will maintain head in the chamber 4, or in other words, a constant differential pressure across the orifice regardless of the amount of back pressure in pipe 15. Because of the arrangement of the conduit 15 connected to the top of the piston 9, whatever back pressure there might be in the line 7 will have no effect whatsoever upon the differential across the orifice 6 but, of course, it would change the actual pressure within the chamber 4. In other words, let us assume that the actual pressure in the chamber 4 is fifteen pounds and the back pressure zero, now if a back pressure should be set up in 7, say, twenty pounds, then the actual pressure in the chamber 4 would be thirty-five pounds, thus leaving a differential head of fifteen pounds the same as before. It will be obvious that the same is true regardless of whether the valve is balanced or unbalanced.

The housing 2 also preferably provides a suitable bearing for supporting a shaft 16 rigidly connected to the variable orifice valve 6 and actuated by means of a suitable lever 17. It will thus be evident that the orifice may be readily adjusted to any predetermined opening by moving the lever 17 to the desired point on the graduated scale at the face of the unit.

The operation of the detailed part of the hydrostatic valve as shown in Fig. 2, and the utilization of the same in controlling the speed of the liquid actuated element may best be understood by describing the operation of the complete liquid circulating system. Referring to Fig. 1, for instance, wherein a simple circuit is shown as comprising a constant displacement type pump 18, a relief valve 19, a four-way control valve 20, a cylinder 21 containing a liquid actuated element or piston 22, a check valve 23, a feed control valve 2, and a tank 24; the liquid flows through the pump 18, relief valve 19 and four-way valve 20, to one end of the cylinder 21, thus exerting pressure on the head of the piston as indicated by the arrows. This pressure tends to move the actuated element or piston 22 in one direction and to force the liquid on the other side of the piston out through the pipe 25. As the check valve 23 will prevent flow therethrough in this direction, the liquid will be forced to enter the chamber 3 of the valve housing 2. The spring 11 will normally hold the valve 5 open and liquid entering from the pipe 25 will fill the chamber 3 and chamber 4 and enter the passageway 13 and fill the chamber 12 thus creating a pressure under the piston 9 tending to move it towards valve closing position. It will be seen that if this pressure should be sufficiently high, it would completely overcome the spring 11 and close the valve 5 against the removable seat 26.

Upon moving the valve 6 by the handle 17 to any selected point, the liquid will flow through this valve and through the pipes and control valve 20 back to the tank. Now, when this valve 6 is open and the liquid allowed to escape from the chamber 4, a pressure drop occurs which will result in the spring 11 opening the valve 5 and admitting additional liquid to the chamber 4 whereby to instantly build up the pressure in the chambers 4 and 12 to thus in turn move the piston 9 upwardly towards valve closing position. As the orifice control valve 6 has been set at a certain position, the outlet of liquid from the chamber 4 will be continuous and therefore the inlet of liquid past the valve 5 would have to be continuous to maintain a pressure in the chamber 4. It will thus be seen that the piston 9 is automatically positioned so that just sufficient liquid is admitted past the valve 5 to the chambers 4 and 12 to maintain pressure necessary to partially overcome the spring 11.

Disregarding the back pressure in line 15, and with the effective areas of the portion 10 and the valve 5 equal, the pressure in the chamber 4 will be maintained constant, for any given spring, regardless of the opening of the orifice provided with a valve 6. Any tendency to increase the pressure in the line and in the chamber 3 will be immediately reflected in the chamber 12 to raise the piston and valve 5 towards valve closing position. Likewise, any pressure drop in the chamber 3 will be immediately reflected in the chamber 12 and the spring 11 will immediately open or enlarge the opening past the valve 5 and admit more liquid to the chamber 4 to maintain pressure therein. Thus, it is seen that uniform pressure is maintained in the chambers 4 and 12 regardless of the pressures in the chamber 3 and since a uniform pressure is maintained in the chamber 4, the flow past the orifice valve 6 must always be at the same rate for a

given position, any viscosity change due to temperature being negligible.

Taking into consideration the varying back pressure in the line 15, the pressure in the chamber 4 will vary in accordance with any variation in the back pressure, but the differential between the pressure in the chamber 4 and that in the line 7 will be maintained regardless of any change in back pressure. Thus it will be seen that with a uniform pressure in chamber 4 or with a uniform differential pressure across the orifice, the flow past such orifice will, of necessity, be constant for any given opening of the orifice 6; if the rate of flow is constant on the exhaust side of the motor, then regardless of the load upon the piston 22 of the motor and up to the capacity of the setting of the relief valve 19, the speed of the piston 22 will be maintained at the rate set above the orifice opening. The relief valve 19 is set to equal the maximum desired load on the piston 22. The speed control unit 2 will, of course, have less capacity, when operating to control the speed of the piston 22, than the capacity of the pump 18. Thus if the pump 18 has a five gallon per minute capacity, and a certain setting of the speed control unit 2 a one-half gallon per minute capacity, and if the maximum load on the piston 22 and the maximum setting of the relief valve 19 should be say two thousand pounds, then if the pump is started up and the liquid directed into the inlet side of the cylinder 21, it will be seen that the back pressure against the piston 22 caused by the small capacity of the speed control unit 2 will cause a maximum pressure to build up on the inlet side of the cylinder 21 and against the relief valve 19, with the result that the excess liquid from the pump will be spilled over the relief valve. It will be obvious that there would be no function in having a hydrostatic valve or flow control unit 2 unless its capacity were less than the pump volume; this excess of the pump over the flow control unit is taken care of by the relief valve.

When the valve 20 is reversed by means of its actuating lever, liquid will pass around the speed control valve assembly 2 and through the check valve 23 allowing a quick return and a rate equivalent to the full volume of the pump 18. During the power stroke of the piston 22, any liquid pumped in excess of the required amount to fill the cylinder 21 at the rate it is allowed to move by the speed regulator valve, is allowed to escape through the relief valve 19 back to the tank.

In the construction of the speed control valve assembly, it is important that the diameter A^1 of the stem at the point 10 bear a certain predetermined relation to the effective diameter A^2 of the valve 5. Normally, these two diameters are preferably equal so that pressure in the chamber 3 will not impart either a downward or upward force on the piston 9. However, in many instances, it might be desired to increase the speed of the liquid actuated element as the load increases, and in this case the effective diameter of the valve 5 will preferably be made smaller than the effective diameter at the point 10 (as shown in Fig. 2). In this case, any drop in pressure in the line 25 due to a sudden load will cause an increase of the pressure in the chamber 4, thus maintaining increased speed during the effective period of said increase in load, as will hereinafter be explained in greater detail.

In order to change my valve assembly to vary 75

the speed with the variation in load, it is possible to remove the valve sleeve 26 and replace with one of a different effective diameter, or it is possible to construct the valve and valve seat 5 (as shown in Fig. 4) so that the seat 26a is fixed and the valve 5a is removable so that valves 5a of different diameters will contact with the seat 26a at different points and thus vary the effective diameter. As shown in Fig. 4, diameter A^3 of valve 5a is larger than A^1 of stem 10. It will thus be seen that by proportioning the relative areas of the valve 5 and valve stem at 10, any decrease in pressure due to load upon the member 22 can be made to increase or decrease pressure in chamber 4 and thus increase or decrease the speed of the member 22.

In Fig. 5 I have shown my hydraulic system as applied to a member to be actuated in which the speed thereof is controlled in both directions. In this circuit the four-way valve 20 controls the flow of liquid under pressure alternately to opposite sides of the piston 22. As shown, this piston 22 may control the actuation of a turret head, or any other machine tool element. The liquid from the discharging side of the cylinder 21 will be directed by the four-way valve 24 to the speed control unit, and this four-way valve will control the application of the pressure to the orifice 6, regardless of the pressure in the chamber 3, in the same manner as described in connection with the operation of the circuit shown in Fig. 1. Inasmuch as both sides of the cylinder 21 discharge through the valve unit 2, it will be seen that the speed of the piston 22 will be accurately controlled in both directions regardless of a negative or positive load against the piston 22. A rapid traverse valve 30 may be inserted as a shunt around the speed control unit 2 to bypass the speed control unit 2 when desired.

I have also indicated in Fig. 5 approximate pressures that might exist in the valve system in a certain condition of operation. With a resistance or load of approximately one thousand pounds and with a piston diameter of four inches and a piston rod diameter of one inch, the pump 18 could be regulated by setting the relief valve 19 to deliver seven hundred and fifty pounds per square inch, which pressure will be directed by means of the valve to the left hand side of the piston 22. To obtain the proper movement of the piston 22 the pressure on the discharge side will be approximately 640 pounds per square inch and approximately this same pressure will be present in the chamber 3 of the unit 2. With a certain spring 11 in the unit 2 and a certain diameter of the piston 9, a pressure of ten pounds per square inch will be maintained in the chamber 4; in this particular case the area of the piston plus the valve stem would be approximately two square inches, and the spring strength twenty pounds. It will be evident that in this arrangement the variable valve 6 may be set to obtain any speed desired of the work element, regardless of a negative or positive load in a single direction of movement and in every such set-up the pressure in the chamber 4 will remain constant at ten pounds per square inch.

In Fig. 6 I have shown a slightly modified hydraulic hook-up wherein the speed control unit 2 is placed in the intake side of the system. This particular hydraulic hook-up may be utilized with many machine tools and other elements and has practically all the advantages of the

system shown in Figs. 1 and 5 with the exception that it would not be as effective in case of a sudden release of the load as in case wherein the drill has protruded through the work and the inertia force of the weight of the drill head would be greater than the force exerted by the vacuum behind the piston.

To more specifically express the operation of the system, assuming that there is no pressure and the entire system, as shown in Fig. 1, is at rest, the lever 17 may be placed in any position to give the required speed. The pump 18 may then be started and the liquid under pressure flows through the four-way valve 20 into the upper end of the cylinder 21. This causes the piston 22 to move, driving the oil on the other side thereof into the control valve 2, the piston of which is at that time held wide open by the spring. As soon as the pressure in chamber 4 builds up due to restriction of the orifice member 6, the pressure on the lower side of the piston 9 overcomes the spring 11 closing the valve 5 to the point where flow through this valve just supplies sufficient volume to maintain a predetermined pressure in the chamber 4.

For example, using a thirty pound spring 11 and a piston 9 of two square inches effective area, it will require a pressure of over fifteen pounds in the chamber 4 to overcome the spring and close valve 5 to shut off inflowing liquid. Assuming the control valve 6 to be open to such a position as to pass five gallons of liquid per minute at fifteen pounds per square inch, the pressure in chamber 4 will drop just sufficient to allow the spring 11 to open the valve 5 and in turn allow liquid to flow into the chamber 4 to maintain the pressure in that chamber at a point which will balance the pressure at fifteen pounds per square inch and, of course, this in turn will maintain the desired pressure differential across the orifice valve 6.

As the valve 6 is opened to obtain a higher speed the resulting expansion of the spring 11 for this greater liquid flow will result in a slight lowering of the maintained pressure in the chamber 4 due to the change of rate of the spring.

Citing another example, if there is a thousand pounds pressure above the piston 22 and five hundred pounds below, and the load should suddenly be released, the piston 9 would move an almost infinitesimal amount because the oil in the control valve 2 is practically incompressible; in other words, a change of only one pound pressure will operate the piston 9 so that even if there would be five thousand pounds pressure in the line the pressure in the chamber 4 would still be constant because normally the effective diameters 5 and 10 of the balanced valve are equal.

On the other hand, it is often desirable to obtain an increase of speed in a hydraulic motor coincident with an increase in load and to accomplish this, referring particularly to Figs. 2 and 4, a sleeve 26 or a valve 5a is selected with a diameter smaller than the diameter of the stem 10. With the smaller area on 5 or 5a any drop in the pressure in chamber 3 will reduce the reaction against the spring 11 and result in a proportionate increase in pressure in 4; in other words, with the control valve balanced the pressure in 4 will always remain constant regardless of conditions in the system, but with the valve unbalanced the pressure in 4 will be proportional to the unbalancing pressure. More specifically, any unequalness in the areas 5 and 10 will add to or subtract from the effective spring load on the

piston and will effect a proportional change in the pressure in chamber 4. An increase or decrease of the pressure in chamber 4 increases or decreases the flow through the valve 6. It will therefore be obvious that with areas 5 and 10 unbalanced a change in pressure in chamber 3 causes a proportional change in chamber 4 which is either in direct or inverse relation to the change in 3 depending upon whether the effective area of 5 is larger or smaller than 10. The main use for this feature is due to the fact that all hydraulic motors have some slip or leakage and an increase in load causes an increase in slip due to the increased pressure differential across the piston and it is therefore possible to select a speed control valve 5 so that a change in load will cause no change in piston speed.

It will be understood that the limited line of contact such as shown in Fig. 4, will be more efficient in the operation of the valve and the maintaining of the contact pressure in the chamber 4. This is because the seat of the sleeve 26a has a fixed taper. It is easy to fabricate discs 5a of various diameters. The sharp edge of the disc 5a contacting with the tapered seat on a line contact makes for an accurate efficient seal; in changing the valve area it is only necessary to change discs 5a. The valve shown in Fig. 2 constitutes merely a reversal of parts, and is less desirable mechanically because of the difficulty in matching two tapered surfaces and because both sleeve 26 and valve 5 must be reversed in changing the setting. There is no difference in the functions or operations of either valve assembly and either may be used equally well in the control units shown in Figs. 1, 5 and 6.

It will be understood here that where the word "maintaining" is used in the specification and claims I am referring to substantial maintenance of pressure or pressure differential, as it will be understood that the speed of some types of machines or units may vary somewhat and still be considered a uniform speed within the meaning of the present invention.

What I claim is:

1. A liquid controlling system comprising in combination a liquid operated motor, a source of liquid under pressure and a speed control device all operatively connected, said device including a control valve having opposed pressure surfaces and a regulable orifice member, said member and valve being operatively connected through a pressure chamber, the pressure in said chamber controlling the flow through the orifice member to control the speed of the motor, said opposed pressure surfaces being unbalanced to maintain a pressure in the pressure chamber in proportion to the unbalancing of said pressure surfaces whereby to increase or decrease the speed of the motor upon a variation in load.

2. In combination, a hydraulic motor, a source of liquid supply operatively connected with the motor, a speed control unit therefor embodying a chamber for receiving the liquid supply, a variable discharge orifice member, a chamber on the intake side of said orifice member, a valve between said two chambers having opposed pressure surfaces, elements forming the effective size of one of said pressure surfaces, one of said elements being replaceable to vary the size of said one surface, and a spring pressed piston operatively connected with said valve for controlling the pressure in said second named chamber to control the pressure differential across the orifice member.

3. In combination, a hydraulic motor, a speed control unit therefor including a chamber for receiving the normal liquid flow from the motor, a second chamber leading to a discharge orifice member of predetermined size, a piston valve having opposed pressure surfaces for controlling the flow between said two chambers, a piston connected to said valve, a conduit for connecting the second chamber with one side of the piston, one of said opposed pressure surfaces being of different relative effective diameter to vary the pressure in the second chamber in proportion with a change in load in the motor.

4. In combination, a hydraulic motor having a piston and cylinder, a hydraulic circuit including a pump directly connected with said motor, a relief valve in said circuit for determining the maximum preloading of one side of said piston, a directional valve for the motor, and a speed control unit comprising a regulable orifice valve, a pressure chamber on one side of said orifice valve and a discharge conduit leading from the unit on the other side, a spring pressed piston having one face exposed to the pressure in said chamber and the other face exposed to the pressure in said discharge conduit, a second chamber for receiving liquid from the motor, the flow of which is to be controlled, and a piston valve formed as a part of said piston and extending into said second chamber, said piston valve having opposed pressure surfaces with different effective areas exposed to the pressure in said second chamber, the relative size of said different effective areas being predetermined to insure a predetermined relationship between the pressure in the first chamber and any change in pressure in the second chamber, and a passageway between said two chambers forming a valve seat for one of said pressure surfaces, said spring tending to separate said pressure surface and valve seat.

5. In combination, a hydraulic motor having a piston and cylinder, a hydraulic circuit including a pump directly connected with said motor, a directional valve for the motor, and a speed control unit comprising a regulable orifice valve, a pressure chamber on one side of said orifice valve and a discharge conduit leading from the unit on the other side, a spring pressed piston having one face exposed to the pressure in said chamber and the other face exposed to the pressure in said discharge conduit, a second chamber for receiving liquid from the motor, the flow of which is to be controlled, and a piston valve formed as a part of said piston and extending into said second chamber, said piston valve having opposed pressure surfaces with different effective areas exposed to the pressure in said second chamber, the relative size of said different effective areas being predetermined to insure a predetermined relationship between the pressure in the first chamber and any change in pressure in the second chamber, and a passageway between said two chambers forming a valve seat for one of said pressure surfaces, said spring tending to separate said pressure surface and valve seat.

6. In combination, a hydraulic motor, a hydraulic circuit including a pump directly connected with said motor, a directional valve for the motor, and a speed control unit comprising a regulable orifice valve, a pressure chamber on one side of said orifice valve and a discharge conduit leading from the unit on the other side, a spring pressed piston having one face exposed

to the pressure in said chamber and the other face exposed to the pressure in said discharge conduit, a second chamber for receiving liquid from the motor, the flow of which is to be controlled, and a piston valve formed as a part of said piston and extending into said second chamber, said piston valve having opposed pressure surfaces with different effective areas, than the area of the faces of said piston, exposed to the pressure in said second chamber, the relative size of said different effective areas being predetermined to insure a predetermined relationship between the pressure in the first chamber and any change in pressure in the second chamber, and a passageway between said two chambers forming a valve seat for one of said pressure surfaces, said spring tending to separate said pressure surface and valve seat.

7. A liquid controlling system comprising in combination a liquid operated motor, a source of liquid under pressure constantly preloading one side of said motor during a power stroke, and a speed control device all operatively connected, said device including a control valve having opposed pressure surfaces of different effective areas and a regulable orifice member, said member and valve being operatively connected through a pressure chamber, a spring pressed piston attached to said valve and subject to the pressure in said chamber, the pressure in said chamber controlling the flow through the orifice member to control the speed of the motor, the effective area of one of said pressure surfaces being predetermined and so arranged relative to the effective area of the other pressure surface that any change in pressure in liquid leading from the motor due to change in load on the motor will predetermine the pressure in said chamber in accordance with said relative effective diameters.

8. A flow control unit, for use with a hydraulic motor circuit of the type having a piston and cylinder motor unit, and pump for applying positive pressure to one side of the piston during its entire working stroke, comprising a regulable orifice valve, a pressure chamber on one side of said valve and a discharge conduit leading from the other side, a spring pressed piston having one face exposed to the pressure in said chamber and the other face exposed to the pressure in said discharge conduit, a second chamber for receiving liquid from the other side of said motor piston, and a piston valve formed as an extension of said piston and extending into said second chamber, said piston valve having opposed pressure surfaces of appreciably smaller size than the effective area of said piston, said pressure surfaces being so proportioned relative to each other as to predetermine the effect of the pressure in said second chamber upon the pressure in said first chamber, and elements cooperating to form the effective area of one of said surfaces, one of said elements being replaceable to change the relation between the effective areas of said opposed surfaces.

9. A flow control unit, for use with a hydraulic motor circuit of the type having a piston and cylinder motor unit, and pump for applying positive pressure to one side of the piston during its entire working stroke, comprising a regulable orifice valve, a pressure chamber on one side of said valve and a discharge conduit leading from the other side, a spring pressed piston having one face exposed to the pressure in said chamber and the other face exposed to the pressure in

said discharge conduit, a second chamber for receiving liquid from the other side of said motor piston, and a piston valve formed as an extension of said piston and extending into said second chamber, and connecting the same with said first chamber, said piston valve having opposed pressure surfaces of appreciably smaller size than the effective area of said piston, said pressure

surfaces being so proportioned relative to each other as to predetermine the effect of the pressure in said second chamber upon the pressure in said first chamber, and means for varying the relative effective area of one of said pressure surfaces.

HARRY F. VICKERS.
